Primary Examiner — Robin V Webster(74) *Attorney, Agent, or Firm* — Cynthia L. Clay; Kim William Zerby(57) **CLAIM**

The ornamental design for a connector for a faucet mounted water filter, as shown and described.

DESCRIPTION

FIG. 1 is a perspective view of a connector for a faucet mounted water filter illustrating my new design;
 FIG. 2 is a left side elevational view thereof;
 FIG. 3 is a right side elevational view thereof;
 FIG. 4 is a front side elevational view thereof;
 FIG. 5 is a back side elevational view thereof;
 FIG. 6 is a top planar view thereof; and,
 FIG. 7 is a bottom planar view thereof.
 The broken lines form no part of the claimed design.
